(57) **CLAIM**

The ornamental design for a downspout extension, as shown and described.

DESCRIPTION

FIG. 1 is a perspective view of the downspout extension showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded view of FIG. 1; and,

FIG. 10 is an exploded view of FIG. 2.

The broken lines are directed to environment and are for illustrative purposes only which form no part of the claimed design.

1 Claim, 10 Drawing Sheets(56)
